UNITED STATES PATENT OFFICE

152,190

DESIGN FOR A PROJECTOR

Carl R. Diedrich, Chicago, Ill.

Application March 17, 1948, Serial No. 145,188

Term of patent 14 years

(Cl. D61—1)

To all whom it may concern:

Be it known that I, Carl R. Diedrich, a citizen of the United States, residing at Chicago, in the county of Cook and State of Illinois, have invented a new, original, and ornamental Design for a Projector, of which the following is a specification, reference being had to the accompanying drawing, forming a part thereof.

In the drawing:

Fig. 1 is a front perspective view of a projector, showing my new design; and

Fig. 2 is a rear perspective view of the projector.

I claim:

The ornamental design for a projector, as shown.

CARL R. DIEDRICH.
